UNITED STATES PATENT OFFICE.

JOHN L. CASLER, OF MANSFIELD, OHIO.

AUTOMATIC SAFETY GAS CUT-OFF.

1,174,825.

Specification of Letters Patent. Patented Mar. 7, 1916.

Application filed February 18, 1915. Serial No. 9,107.

To all whom it may concern:

Be it known that I, JOHN L. CASLER, a citizen of the United States, residing at Mansfield, in the county of Richland and State of Ohio, have invented certain new and useful Improvements in Automatic Safety Gas Cut-Offs, of which the following is a specification.

My present invention relates to new and useful improvements in automatic cutoffs for gas burners of stoves and furnaces, the primary object of my invention being the provision of a cutoff valve which may be manually opened to permit flow of the gas to the burner when the latter is to be lighted and which will automatically close, after a predetermined lapse of time, if for any reason the burner is not lighted or after being lighted, the light is extinguished.

A further object of my invention is to provide an automatic cutoff for the above-described purpose, which will be thermostatically operated, being controlled by a pilot light operating in conjunction with the burner proper, the pilot light and burner being so constructed and arranged with respect to each other that either one, if lighted, will light the other.

A still further object of my invention is to so arrange the cutoff mechanism and its valves that a single valve will control the flow of gas from the fuel supply pipe to both the main burner and the pilot light, this being the valve which the automatic cutoff closes, the result being that operation of the cutoff not only prevents escape of gas from the burner, but also from the pilot light.

A still further object of my invention is to so arrange the automatic cutoff mechanism that while thermostatically operated, the actual cutting off or closing of the valve is mechanically performed, this mechanism being such that a predetermined lapse of time is necessary, after operation of the thermostatic means, before the mechanical means will close the valve. Because of this arrangement, it is unnecessary to manually hold the valve in open position until the thermostatic means has become sufficiently heated to prevent its action or to provide any secondary holding means for the valve during such time.

With these and other objects in view, my invention will be more fully described, illus-

trated in the accompanying drawings and then specifically pointed out in the claims which are attached to and form a part of this application.

In the drawings:—Figure 1 is a front elevation of my automatic gas cutoff applied to a conventional type of stove; Fig. 2 is a vertical sectional view taken on the line 2—2 of Fig. 1; Fig. 3 is a horizontal sectional view taken on the line 3—3 of Fig. 2, the burner and cutoff mechanism itself being shown in plan view; Fig. 4 is a detail plan view of the burner mechanism, parts being shown in section; Fig. 5 is a sectional view through the casing inclosing the valve closing mechanism proper; Fig. 6 is a fragmentary perspective view of a portion of the valve closing mechanism; Fig. 7 is a view corresponding to Fig. 5, but illustrating a somewhat modified structure.

Corresponding and like parts are referred to in the following description and indicated in all the views of the drawings by the same reference characters.

In the drawings, which illustrate the preferred form of my invention, 10 indicates the fire box of a conventional stove or furnace, having a wall 11 provided with an opening 12 and an opening 13, the latter being above and at one side of the former opening. The burner is, of course, mounted in the fire box of the stove, being supported therein, in any suitable manner, not shown, and may be of any desired type or pattern. In the present instance, I have illustrated the burner in the form of a cylindrical tube 14 closed at each end and provided in its upper face with a plurality of spaced perforations 15 through which the gas to be burned passes. This burner is provided near one end with a transverse partition wall 16 and pipes 17 and 18 lead into the burner at opposite sides of the partition wall.

As will be appreciated, this construction in effect provides two burners, each having an independent source of fuel supply, a portion of the perforations 15 being also formed at either side of the partition wall 16 and the burner, when in place, projecting out of the stove through the opening 12 so that the partition wall 16 is somewhat outside of the stove. A housing 19, in the form of a U-shaped pipe section, establishes communication, exteriorly of the stove, between the openings 12 and 13, the lower portion of this

- housing 19 being cut-away to straddle and surround the outwardly extending end of the burner, as best shown in Fig. 2 of the drawings. This housing serves to conduct 5 the burnt gases from the smaller chamber of the burner, which part will be termed the pilot light, to the stove or furnace and also to inclose the thermostatic valve controlling mechanism, as will be later explained.
- 10 The perforations 15 are so formed both in the burner proper and in the pilot portion thereof that lighting of gas at the pilot light will cause lighting of the burner. Furthermore, if either the pilot light or burner is 15 lighted and the other extinguished, through any cause, the extinguished portion of the burner will be relighted by that part which remained lighted.

The pipe 17 is provided at its free end 20 with an air mixer 20 of any desired or suitable type and the pipe 18 with an air mixer 21. A three-way valve casing 22 connects the mixer 20 to the fuel supply pipe 23 and a pipe 24 connects the free port of this 25 three-way valve with a fuel controlling valve 25 which is also connected to the air mixer 21. This latter fuel controlling valve 25 is preferably in the form of a needle valve in order that careful adjustment may 30 be insured. The three-way valve casing 22 incloses a cylindrical valve plug 26 having a diametrically extending passage 27 adapted to establish communication between the pipe 23 and mixer 20 and having its peripheral face grooved or channeled, as shown at 28 to establish a reduced communication between the pipes 23 and 24 when the valve establishes communication between the pipe 23 and mixer 20. It will therefore be clear 40 that the valve 26 controls the supply of gas both to the main burner and to the pilot light and that as long as gas passes to either the main burner or pilot light, it will pass to both until the valve 25 is intentionally 45 closed. The valve plug 26 is provided with a valve stem 29 to receive a radially extending handle 30 which projects completely through the valve stem. The extended portion of this handle terminates in an eye 31 50 and a link 32 pivotally connects this eye with the free end of a lever arm 33, the opposite end of which is swingingly mounted upon the outer end of a shaft 40 journaled in opposite walls of a housing 35, the housing 55 being supported upon a suitable bracket 36. It should be carefully noted that the lever 33 is free to turn independently of the shaft 40.

Interiorly of the housing, a second shaft 60 34 carries a brake wheel 37 and pinion 38. A train of gears, indicated as a whole by the numeral 39, are disposed to transmit movement from the shaft 40 to the shaft 34, being proportioned to turn the shaft 34 at a much 65 higher rate of speed than the shaft 40. In

order to govern the speed of turning of the shaft 34, such shaft is provided with a fan 41 or other suitable form of governor. The shaft 40 constitutes the drive shaft of the train of gears and coiled about it is the 70 drive spring 42, one end of which is secured to the shaft and the opposite end of which is secured to the casing, as shown at 43.

The free outer end of the shaft 40 carries 75 a crank arm 44 having a handle 45 by means of which the shaft 40 may be manually turned against the action of the spring 42 and this crank arm, at its free end, is provided with a rearwardly directed lug or 80 shoulder 46 adapted to engage the free end portion of the lever 33.

Mounted on the same bracket 36, which supports the housing 35, is a bell crank lever 47, and a link 48, connected to one arm of 85 this lever, extends through the adjacent wall of the casing 35 and is screw threaded, as shown at 49, in Fig. 5. A pin 50 supports one end of a resilient brake arm 51 in such a manner that the brake arm may be swung 90 into and out of engagement with the brake wheel 37. This brake arm is bowed intermediate its length toward the brake wheel and has its free end bent at an angle to its body portion and provided with a laterally 95 directed terminal 52 apertured to receive the threaded end of the rod or link 48. Clamping nuts 53 are threaded upon the link, one upon either side of the terminal 52 of the brake arm to clamp the link and 100 brake arm together. It will, therefore, be clear that turning movement of the bell crank lever 47 will cause swinging of the brake arm 51 into or out of engagement with the brake wheel 37. The bracket 36 is provided with a lateral extension projecting 105 longitudinally of the housing 19 and a lever 54 is pivotally mounted intermediate its length upon the free end of this extension of the bracket. A link 55 pivotally connects 110 the free end of the bell crank lever with one end of the lever 54 and a second link 56 is pivotally connected to the opposite end of the lever 54 and has its free end passed through an outstanding ear 57 formed upon 115 the bracket 36 adjacent the bell crank lever 47, movement of the link 56, in a direction away from the lever 54, being adjustably limited by a milled nut 58 threaded upon the link 56 and engaging the ear 57. The 120 links 55 and 56 are thermo-expansible, being formed of any suitable metal or other material capable of unusual expansion upon heating.

In describing the operation of my thermostatic gas cutoff, I will assume that at 125 the beginning the main cutoff valve 26 is closed. Under these conditions, the shoulder 46 of the crank arm 44 bears against the free end of the arm 33 to hold the valve in 130

closed position. In order to open the valve and permit lighting of the burner, the crank arm 44 is swung away from the arm 33 through almost a complete revolution. Under these circumstances, the valve handle 30 may be manually swung to open the valve 26 and permit flow of gas to both the pilot light and burner, these being then lighted in the usual manner. As soon as the crank arm 44 has been released, the spring 42 sets the train of gears 39 in movement and causes the crank arm 44 to start back to its original position, this movement being, however, relatively slow, due to the proportioning of the gears employed. For this reason, the pilot light will have ample time to sufficiently heat the thermo-expansive links 55 and 56 to cause them to expand before the crank arm will reach the arm 33. The expanding of these links 55 and 56 acts through the links 54 and 47 to operate the connecting rod or link 48 to swing the brake arm 51 into engagement with the brake wheel 37 and so prevent further movement of the train of gears, and consequently of the crank arm 44. The valve is, therefore, still open and will remain open until the expansive links 55 and 56 become sufficiently cooled to release the brake arm 51. It will therefore be clear that as long as the pilot light, and consequently the burner, remain lighted, the crank arm 44 will be held against movement and the valve 26 will remain open. This valve 26 may, however, be manually closed at any time without any hindrance from the automatic closing mechanism.

If the burner is extinguished for any reason, either accidentally, or by manually closing the valve 26, the thermo-expansive links 55 and 56 will contract and swing the brake arm 51 out of engagement with the brake wheel when the spring 42 will cause turning of the shaft 40 to bring the crank arm 44 into engagement with the arm 33, to swing such arm to a position to close the valve 26, if the valve has not already been manually closed.

If preferred, the shaft 40, instead of carrying the spring 42, may be provided with a winding drum 60 to which is attached one end of a cord 61, the greater portion of which is wound about the drum, the free end being provided with a weight 62. It will of course be clear that the strain of the weight upon the cord wound about the drum will tend, at all times, to turn the shaft 40 in the same manner as the spring 42 does in the form previously described.

It will be understood that the invention is not to be limited to the specific structure shown in the drawings and described in the specification, as any changes, within the scope of the appended claims, may be made at any time, without departing from the spirit of my invention. It will also be un-

derstood that although I have illustrated and described my automatic cut-off in connection with a burner for a stove, it is equally applicable to burners for illuminating purposes or furnaces and by the term 70 burner I intend to include any device for consuming gas either for the purposes of light or heat.

Having thus described the invention, what is claimed as new is:

1. An automatic cutoff valve for gas burners including a burner and pilot light therefor, a valve controlling supply of fuel to both the burner and pilot light and including a revoluble handle, a shaft, an arm 80 swinging on the shaft, a link connecting the arm and handle, an arm fixed to the shaft to turn therewith and adapted to engage the first arm to swing it and the handle, means tending to constantly turn the shaft, a brake 85 wheel adapted, when held, to hold the shaft against turning, a brake arm movable into and out of engagement with the brake wheel, and thermostatic means subject to the heat of the pilot light for controlling the brake 90 arm.

2. An automatic cutoff valve for gas burners including a burner and pilot light therefor, a valve controlling supply of fuel to both the burner and pilot light and including a revoluble handle, a shaft, an arm swinging on the shaft, a link connecting the arm and handle, an arm fixed to the shaft to turn therewith and adapted to engage the first arm to swing it and the handle, means 100 tending to constantly turn the shaft, a brake wheel adapted, when held, to hold the shaft against turning, a brake arm movable into and out of engagement with the brake wheel, and thermostatic means subject to the heat 105 of the pilot light for controlling the brake arm, said means including a bell crank lever a link connecting one arm of the bell crank lever with the brake arm, and a thermo-expansive device operatively connected to the 110 other arm of the bell crank lever and disposed to receive heat from the pilot light.

3. In an automatic cutoff for gas burners, the combination with a gas burner having a pilot light, of a housing surrounding and extending from the pilot light, a bracket, a lever pivoted intermediate its length upon the bracket, a bell crank lever, a thermo-expansive link fixedly secured at one end and pivotally connected to one end of the first lever, 115 a second thermo-expansive link pivotally connecting the free end of the first lever with one arm of the bell crank lever, a link pivotally connected to the free arm 120 of the bell crank lever, a locking device connected to the free end of the last named link, a valve controlling flow of fuel to the burner and pilot light, and means constantly tending to move into position to close the 125 valve, said means being controlled in its ac- 130

- tion by the locking device which is releasable by contraction of the thermo-expansive links.
4. An automatic cutoff for gas burners including a burner and pilot light therefor, a valve controlling supply of fuel to both the burner and pilot light and including a revolute handle, a shaft, an arm swinging on the shaft, a link connecting the arm and handle, an arm fixed to the shaft to turn therewith and adapted to engage the first arm to swing it and the handle, means tending to constantly turn the shaft, means for governing the speed of turning of the shaft, a brake wheel adapted when held to hold the shaft against turning, a brake arm movable into and out of engagement with the brake wheel, and thermostatic means subject to the heat of the pilot light for controlling the brake arm.
5. In a cut off valve for stove burners, the combination with a stove having spaced openings formed in the wall thereof, of a combined burner and pilot light extending through the first opening, a housing surrounding the pilot light and extending exteriorly of the stove and communicating with the second opening, a cut off valve controlling supply of fuel to both the pilot light and burner, means set in operation by opening of the valve for subsequently closing it, and thermostatic means in the hous-
- ing for preventing operation of such last mentioned means when the pilot light is burning. ³⁵
6. An automatic cut off for burners including a valve adapted to control supply of fuel to the burner, a revolute handle for the valve, a shaft, an arm swinging on the shaft, a link connecting the arm and handle, an arm fixed to the shaft to turn therewith and adapted to engage the first arm to swing it and the handle, means tending to constantly turn the shaft, and thermostatic means adapted to be exposed to the heat of a burner and operable when heated to hold the shaft against turning.
7. An automatic cut-off valve for burners including a valve adapted to control the supply of fuel to the burner, a revolute handle for the valve, means constantly tending to move into position to engage the handle and close the valve, a brake mechanism adapted, when engaged, to hold such means against movement toward the handle, and thermostatic means adapted to be subjected to the heat of the burner for controlling the brake. ⁵⁰
- In testimony whereof I affix my signature in presence of two witnesses.
